US00D822314S

(12) **United States Design Patent** (10) Patent No.: **US D822,314 S**
(45) Date of Patent: **** Jul. 10, 2018**

(54) **MEAT-BASED PRODUCT**

(71) Applicant: **Salvatore Coppola**, Rho (IT)

(72) Inventor: **Salvatore Coppola**, Rho (IT)

(**) Term: **15 Years**

(21) Appl. No.: **29/505,083**

(22) Filed: **May 18, 2015**

(30) **Foreign Application Priority Data**

Nov. 18, 2014 (EM) 002580480

(51) **LOC (11) Cl.** **01-01**

(52) **U.S. Cl.** ..... **USPC D1/120; D1/130**

(58) **Field of Classification Search**

USPC D1/100-130, 199; 426/5, 76, 87, 92, 94, 426/95, 99, 101, 103, 104, 108, 134, 426/138-139, 143, 144, 279, 282, 283, 426/391, 514, 549, 559, 560, 660, 808; D30/60; D11/1, 86; D24/101-104, 211, D24/212, 215; D21/386, 658, 460;

D23/207

CPC B26D 3/11; A47J 37/043; A47J 37/049; A47J 43/18; A22C 17/006
